(57) **CLAIM**

The ornamental design for a land clearing tool, as shown and described.

DESCRIPTION

FIG. 1 is an isometric view of a land clearing tool;
FIG. 2 is a rear isometric view thereof;
FIG. 3 is a right side view thereof;
FIG. 4 is a left side view thereof;
FIG. 5 is a top view thereof;
FIG. 6 is a bottom view thereof;
FIG. 7 is a front view thereof; and,
FIG. 8 is a back view thereof.

The line shading in FIGS. 1-8 represents contour and not surface ornamentation. The dot-dash lines define the bounds of the claimed design and form no part thereof. The broken lines illustrate portions of the land clearing tool that form no part of the claimed design.

The broken line showing of the front part of the land clearing tool is included for the purpose of illustrating unclaimed portions of the land clearing tool and forms no part of the claimed design.
